UNITED STATES PATENT OFFICE.

EDWARD W. OWENS, OF WAGNER, SOUTH DAKOTA.

CULTIVATOR.

1,369,981.

Specification of Letters Patent. Patented Mar. 1, 1921.

Application filed August 12, 1918. Serial No. 249,404.

To all whom it may concern:

Be it known that I, EDWARD W. OWENS, a citizen of the United States, and a resident of Wagner, in the county of Charles Mix and State of South Dakota, have invented 5 certain new and useful Improvements in Cultivators, of which the following is a specification.

The present invention aims primarily, to 10 provide an improved three row cultivator.

A further object of the invention is the production of a cultivator embodying improved means for shifting the cultivator beams laterally.

15 Still a further object of the invention is the production of a three row cultivator so constructed that the supporting wheels travel on opposite sides of the center one of three rows of corn.

20 Furthermore, the invention contemplates a three row cultivator embodying an improved draft rigging.

Still another object of the invention is the production of a three row corn-cultivator, 25 comparatively light in weight and inexpensive in construction, yet thoroughly durable and efficient in operation.

With these and other objects in view, the 30 invention consisting in the construction, combination, and novel arrangement of parts will be fully understood from the following description, reference being had to the accompanying drawings which form a part of this application, and in which like 35 characters of reference indicate corresponding parts throughout the several views, of which,—

Figure 1 is a plan of a cultivator constructed in accordance with the invention;

40 Fig. 2 is a side elevation of the same;

Fig. 3 is a fragmentary rear elevation of the same;

Fig. 4 is a front elevation of the front truck;

45 Fig. 5 is an enlarged plan of one of the beam-shifting elements and associated parts;

Fig. 6 is a side elevation of the same, 50 parts being cut away and the rear frame member and shift bar being taken in section on the line 6—6 of Fig. 1;

Fig. 7 is a front elevation of one of the shaft bearings; and

55 Fig. 8 is an inverted plan of the front frame member and the draft rigging.

While I have illustrated and hereinafter described the preferred embodiment of the invention, I would not be understood as being limited to the specific structure chosen for illustration, for various alterations and 60 modifications may be made in the details of construction and arrangement of parts without departing from the spirit and scope of the invention as defined in the appended claims.

65 Referring now to the illustrations, the machine consists, essentially, of a main-frame, preferably including front and rear cross members, 9 and 10, respectively, interconnected by suitable side members, 11, and 70 intermediate longitudinal members, 12. The frame is reinforced by a V-shaped bar, 13, which rests upon and is secured to the frame, the rear ends of the arms being secured adjacent the rear corners of the frame 75 and the apex of said V-shaped bar being positioned forward of the center of the front cross member and secured to a plate, 14, below which is the front truck embodying a 80 bolster, 15, pivoted to the plate, 14, as by a king-bolt, 16, the bolster being provided with forks, 17, in which are journaled travel wheels, 18. To the bolster is secured a suitable tongue, 19.

85 The main-frame is supported by a U-shaped axle, 20, the web of which is journaled in suitable bearings, 21, mounted on the two intermediate frame members, 12. The end portions of the axle are extended laterally in opposite directions as at, 22, and 90 on the said extended portions are journaled travel wheels, 23. The extreme ends of the axle arms are rotatably supported in the lower ends of bars, 24, the upper ends of which are pivoted as at 25, to the main 95 frame. To the under side of the intermediate frame members, 12, are pivoted bars, 26, the other ends of which are adjustably secured to the bars, 24, to hold the latter against forward and rearward movement.

100 It is evident the machine may be raised or lowered on the travel wheels by accordingly shifting the point of connection between the bars, 26 and 24.

105 The travel wheels, 23, are so disposed as to travel on opposite sides of the center of three rows of corn represented by the dotted lines, 27.

110 The machine is provided with six gangs of cultivator plows or other earth working

devices, the two intermediate gangs being so positioned as to turn the soil on opposite sides of the center corn row and the other gangs being positioned outside the travel 5 wheels to cultivate the outer rows, and each gang includes a pair of interconnected beams, 28, carrying plows or other earth-working devices, 29, the forward ends of the beams being pivotally secured to suitable 10 bracket arms, 30, depending from the forward cross member. Means are provided for holding the shovels in yieldable engagement with the earth and for raising the beams. For this purpose I provide for each 15 gang an upright, 31, the lower end of which freely penetrates a member, 32, interconnecting the pair of beams.

Two rock-shafts, 33, are provided, for controlling the uprights, one for each three 20 gangs. The said shafts are journaled in bearings, 34, mounted on the frame. The shafts carry crank-arms, 35, pivoted respectively to the upper ends of the uprights. The shafts are actuated by levers, 36, ful- 25 crumed on quadrants, 37, and provided with detents, 38, engageable with the quadrants to hold the levers in any desired positions.

Between the members, 32, and shoulders, 39, on the uprights, 31, are interposed compression-springs, 40, and the lower ends of the uprights are provided with heads or bosses, 41, to raise the beams when the levers, 36, are depressed. When the said levers are raised it is evident the compression-springs, 40, will hold the plow yieldably 35 engaged in the earth.

To afford means for simultaneously shifting the rear ends of the beams laterally to correct the positions of the earth working 40 devices with respect to the rows of corn, I provide mechanism preferably consisting of a bar, 42, slideable adjacent the rear face of the rear cross member, 10, in suitable guides consisting of U-shaped members, 43, secured 45 to the cross member, 10, and slidably inclosing the bar, 42. The bar, 42, is provided with longitudinal slots, 44, and the portions of the bar at the upper edges of the slots travel on friction-rollers, 45, rotating on 50 bolts, 46, extending through the webs of the guides, 43, and the rear cross member, 10. The shifting bar is provided with a centrally-located upwardly disposed arm, 47, for shifting the bar transversely of the machine. From the under side of the bar, 42, depend rods, 66, the lower ends of which are 55 inclosed by bearings, 67, mounted on the beams, 28. The rods, 66, are suitably secured against lateral movement, relative to the shifting bar, 42, as by diagonal braces, 68, secured to the rods and the bar, 42, the said braces preferably being positioned on the sides of the rods remote from the adjacent corn rows. For shifting the bar I

provide two foot-power actuated devices 65 mounted on the longitudinal frame members, 12, and consisting of longitudinally-disposed tubular shafts, 48, rotatable on rods, 49, supported by rear bearings, 50, mounted on the rear cross member, and front bearings, 51, mounted on the longitudinal members, 12, and having depending forks, 52, between which are free to move vertically the forward end portions of foot-levers, 53. To the ends of the said foot levers are secured flexible links, 54, passing around direction pulleys, 55, journaled in the forks, 52, and wound on the front ends of the tubular shafts, 48, or upon drums, 56, thereon. To the intermediate portions of 70 the levers, 53, are secured flexible links, 57, which are wound upon the rear portions of the shafts, 48, or upon drums, 58, thereon, and secured to the arm, 47.

The rods, 49, are extended toward each 85 other from the bearings, 50, and are then extended rearwardly as at, 59, and on the said extended portions is mounted the driver's seat, 60.

By virtue of this construction it is evident 90 that as one of the foot-levers, 53, is depressed at its rear end, the associated link being wound upon the shaft, 48, will rotate the latter and co-act with the arm, 47, in shifting the bar, 42, in the direction of the 95 depressed lever. As the rear end of the foot-lever is depressed the front end thereof rises and co-acts with the link, 57, in drawing the arm, 47.

The draft rigging preferably consists of 100 a cable, chain or other flexible element, 61, positioned below the front cross member, 9, and having its end portions passing around direction-pulleys, 62, mounted on a flange, 63, depending from the cross member, 9; 105 and extended forwardly through the flange. The extreme ends of the flexible element, 61, are provided with hooks, 64, or other suitable means for attachment to whiffle-trees, 65, or other devices, to which draft animals 110 may be hitched. This draft rigging thus affords means for equalizing the draft.

It is clear that in the construction now disclosed the driver can have no difficulty in 115 watching his alignment, inasmuch as he is seated directly over the center row.

Having thus described my invention, what I claim as new and desire to secure by Letters Patent of the United States, is,—

A cultivator comprising a wheeled frame, 120 a plurality of earth-cultivating devices carried thereby and movable laterally with respect thereto, a bar interconnecting the devices to move them in unison, and means for shifting the bar in opposite directions, including two rotatable members on the frame, 125 depressible levers therebelow, flexible links interconnecting said bar and intermediate

points of the levers and wound upon said members, whereby alternate depression of the levers will accordingly shift the bar in opposite directions, pulleys journaled below 5 the levers, and flexible links wound on the rotatable members, passed around said pulleys and secured to the ends of the levers,

whereby said lever ends, when raised by depression of their opposite ends, coact with the latter links in rotating said members. 10

In testimony whereof I have hereunto set my hand this 7th day of Aug., 1918.

EDWARD W. OWENS.
